(57) **CLAIM**

The ornamental design for a socket organizer, as shown and described.

DESCRIPTION

FIG. 1 is a top plan view of the socket organizer showing my new design;

FIG. 2 is a side elevation view of the socket organizer shown in FIG. 1;

FIG. 3 is a perspective view of the socket organizer shown in FIG. 1;

FIG. 4 is an end view of the socket organizer shown in FIG. 1;

FIG. 5 is a top plan view of a socket organizer showing my new design;

FIG. 6 is a side elevation view of the socket organizer shown in FIG. 5;

FIG. 7 is a perspective view of the socket organizer shown in FIG. 5;

FIG. 8 is an end view of the socket organizer shown in FIG. 5;

FIG. 9 is a top plan view of a socket organizer showing my new design;

FIG. 10 is a side elevation view of the socket organizer shown in FIG. 9;

FIG. 11 is a perspective view of the socket organizer shown in FIG. 9;

FIG. 12 is an end view of the socket organizer shown in FIG. 9;

FIG. 13 is a top plan view of a socket organizer showing my new design;

FIG. 14 is a side elevation view of the socket organizer shown in FIG. 13;

FIG. 15 is a perspective view of the socket organizer shown in FIG. 13;

FIG. 16 is an end view of the socket organizer shown in FIG. 13;

FIG. 17 is a top plan view of a socket organizer showing my new design;

FIG. 18 is a side elevation view of the socket organizer shown in FIG. 17;

FIG. 19 is a perspective view of the socket organizer shown in FIG. 17;

FIG. 20 is an end view of the socket organizer shown in FIG. 17;

FIG. 21 is a top plan view of a socket organizer showing my new design;

(Continued)

FIG. 22 is a side elevation view of the socket organizer shown in FIG. 21;

FIG. 23 is a perspective view of the socket organizer shown in FIG. 21; and,

FIG. 24 is an end view of the socket organizer shown in FIG. 21.
